UNITED STATES PATENT OFFICE.

JOHN LAUNCELOT CAPEL MERCER, OF COBHAM, ENGLAND.

ROUNDING AND BACKING MACHINE FOR BOOKBINDING.

1,237,537.

Specification of Letters Patent. Patented Aug. 21, 1917.

Application filed December 12, 1914. Serial No. 876,866.

To all whom it may concern:

Be it known that I, JOHN LAUNCELOT CAPEL MERCER, a subject of the King of Great Britain, residing at Bookham Lodge, Cobham, in the county of Surrey, England, but now serving abroad with His Majesty's military forces during the war, have invented new and useful Improvements in Rounding and Backing Machines for Bookbinding, 10 of which the following is a specification.

The present invention relates to an improved machine for rounding and backing books to the required curvature and with the shoulder desired, the construction of which 15 will be much simpler and much less costly than machines hitherto employed for this purpose, while its operation will be automatic and require less labor and attention.

A machine constructed according to my 20 invention is illustrated in the accompanying drawing, in which—

Figure 1 is a side elevation of the machine, and

Fig. 2 an end view thereof. 25 Fig. 3 is a plan view of the toggle arms for closing the gripping jaws to hold the book while it is being rounded and backed.

Fig. 4 is a longitudinal section of one of the rollers for raising the book between the 30 gripping jaws.

Figs. 5 to 9 inclusive are detail views of the carrier device for imparting the movement of translation to the books to bring them consecutively into position for being 35 raised to the gripping jaws, and removing them from the machine after completion of the rounding and backing operation, and of the means for tripping such carrier device at the required times; the horizontal bar 40 being in these figures disposed vertically for convenience of illustration.

Fig. 10 is an elevation of the opposite end of the machine to that shown in Fig. 2 showing the means for operating the carrier. 45

Fig. 11 an elevation and Fig. 12 a plan drawn to a larger scale and illustrating the supporting bar for the books and the means for adjusting the height thereof.

Fig. 13 is a sectional elevation drawn to a 50 larger scale showing clamping jaws for holding the book and the backing roller for operation thereon, and the manner of actuating same.

According to my invention the sheets in 55 the collected form to constitute the book are as shown at *a* in Figs. 1 and 2 introduced

either mechanically or by hand vertically on edge and with the back at the top between two stationary guide plates or cheeks 1 suitably supported on the side frames 2 of the 60 machine at the required distance apart to admit the book or publication *a* for which the machine is to be employed between them, and which distance may if desired be adjustable to suit books of different thicknesses. For this purpose the cheeks 1 may be of angle form as shown in Fig. 2 and the base of each be slotted to receive a screw 200, for fixing them in the position to which they have been set.

The book *a* rests with its front edge constituting the under side on the convex upper surface of a stationary bar 3 supported in the side frames 2 centrally below the vertical guide cheeks or plates 1, the curvature 75 of such upper surface being approximately that which it is desired to impart to the back of the book, the weight of which latter tends to cause the front edge of the leaves constituting the same to adapt themselves to 80 such curvature.

A carrier bar or frame 4 is mounted to reciprocate longitudinally below the guide cheeks or plates 1 and at its rear end is provided with a hinged part or trigger plate 5 35 which during the rearward travel occupies its inoperative position clear of the book *a* which has been introduced between said cheeks or plates 1. When the carrier bar or frame 4 arrives at the extremity of its rearward course the trigger plate 5 is mechanically moved to a position behind the rear edge of the book *a*, and caused to carry same forward along the stationary bar 3 on the next forward travel of the carrier frame 4. 95

A suitable arrangement for operating the trigger plate 5 at the required times is illustrated in detail in Figs. 5 to 9 inclusive, in which such plate is acted upon by a spring 6 tending to move it to its operative position behind the rear of book *a*. On the forward travel of carrier 4 the trigger plate 5 passes beyond a hinged trip lever 7, mounted on one of the side cheeks 1, and which on the return movement acts on said plate and causes it to turn on its pin to its inoperative position, where it is retained by the engagement of a small projection 8 in a suitable recess. This movement brings a heel piece 9 on trigger plate 5 in the path of an 100 abutment 10 situated on a flange of one of the guide cheeks 1 in a suitable position to 105 110

act thereon on the completion of the rearward travel of the carrier bar 4, and so turn the trigger plate back to its operative position. A pin 11 engaging a slot in the trigger plate limits the extent of its movement in relation to the carrier bar 4.

The forward travel of the carrier bar 4 (toward the right as shown in Fig. 1) carries the book *a*, which is engaged by the trigger plate 5, to a position beneath the longitudinal rollers 12. These rollers are situated a sufficient distance above the tops of the guide cheeks 1 to allow the book to pass below them and they are normally a distance apart somewhat greater than the thickness of the book to be operated upon, being adjustable to different distances to suit books of different thicknesses.

In its forward movement the book *a* will have been carried between the guide cheeks 1 and along the supporting bar 3 to a position where it will rest on a portion 3^x of the latter which is capable of a vertical upward movement, which may be imparted thereto at the required time through the link 13 lever 14 pivoted to the countershaft 15 and carrying a roller 16 engaging a grooved cam 17 on cam shaft 18 mounted in bearings and suitably actuated in the side frames 2. The rise of the portion 3^x of the supporting bar 3 will bring the book it carries to the position *a*^x between the longitudinal rollers 12, which are then caused to grip same. For this purpose one of the rollers 12 is mounted at one extremity of a rocking lever 19, the other end of which is by a link 20 connected to a bell crank lever 21 mounted on countershaft 15 and one arm of which carries a roller 22 engaging a grooved cam 23 mounted on cam shaft 18. A screw adjustment 24 enables the movement of the rocking lever 19 to be regulated in order to adjust the grip of rollers 12 to suit books of different thicknesses.

In order to allow the supporting bar 3 to be adjusted to insure the portion 3^x thereof raising books of different widths to the required position between the rollers 12, said bar is composed of a lower part 103, 103^x, to which the operating link 13 is pivoted, and to which the bar proper 3, 3^x, is connected by screws 45 working through worm wheels 46^x engaging worms 46 mounted on a shaft 47 capable of rotating in bearings on the lower part 103, 103^x, of the bar, and fitted with a crank 48 for actuating same. The shaft 47 comprises two sections disposed in alignment. The outer section of said shaft 47 is movable toward and from the inner section thereof and a coupling 49, the complementary parts of which are located on adjacent ends of said sections, operates to couple them. A spring 50 normally holds the coupling in the disconnected position and allows the parts 3^x and 103^x to rise together.

When coupling 49 is connected the rotation of shaft 47 will raise or lower the part 3, 3^x, of the supporting bar simultaneously in relation to the lower part 103, 103^x, thereof, to the position suitable for the width of book 70 to be operated upon, and on the release of said shaft 47 the spring 50 will automatically effect the disconnection of the coupling.

When the book *a*^x has been gripped by the rollers 12 a rotary movement is imparted to the latter in the direction to raise the book, with the result of imparting the required rounding to the upper edge or back thereof. A suitable manner of rotating the rollers 12 80 consists in the employment of flexible bands 25 one extremity of each of which rolls around the spindle of one of the rollers 12, while the other extremity is secured to a slide 26 mounted to reciprocate vertically 85 in grooves or ways in one of the side frames 2. The slide 26 is by link 27 connected to a lever 28 pivoted to the countershaft 15 and carrying a roller 29 engaging a grooved cam 30 on the cam shaft 18.

For effecting the return movement of the rollers 12 at the required time a suspended weight may be applied to each roller so as to act against the pull of the bands 25, or said rollers may be constructed as illustrated in Fig. 4, where a spring 44 which is placed under tension by the downward pull of said bands is employed for causing the rollers to rotate in the reverse direction when the slide 26 is caused to rise.

The rotation of the rounding rollers 12 carries the book *a*^x upward until the rounded back passes between a pair of clamping jaws 31, the upward movement being arrested when a certain determined portion of the back of the book projects above such jaws. One of the jaws 31 is stationary, while the other is mounted to slide in ways on the top of the side frames and is operated to grip the book *a*^x at the required time, through 110 the toggle levers 32 pivoted to the bar 33 fixed to the side frames 2, and connected with the actuating link 34, carrying roller 35, which engages a cam groove of the cam 36 mounted on the cam shaft 18.

When book *a*^x has been gripped between the jaws 31, 31, with the rounded back projecting above such jaws to the required extent, a back-forming roller 37 is then by a transverse movement brought into a position 120 centrally above such back.

For this purpose the roller 37 is mounted in bearings 38 carried by arms 39 pivoted to a sliding bracket or block 40, which is connected to toggle arms 41 pivoted to the bar 33 and operated by the arm 42 carrying roller 43 which engages a cam groove in cam 44 mounted on cam shaft 18.

The distance between the back forming roller 37 and the pair of rounding rollers 130

- 12 which bring the upper edge which constitutes the back of book a^x in contact therewith should be regulated so that the movement of the latter may continue for a sufficient length of time to insure that the action produced by the grip of the rollers 12 on the leaves of the book in its travel will impart the amount of curvature which is required to the back thereof.
- 10 When the back of the book has been carried upward to the required position, the clamping jaws 31 close and grip the book a^x with the small portion projecting up beyond same the distance requisite to permit 15 of the formation of the shoulder on either side, and adjacent to the rounded back when same has been completed.

The jaws 31 are fitted with removable clamping cheeks 31 x the thickness of which 20 will be such to allow of the distance between same when closed varying to suit the requirements of books of different thicknesses, and their height and the curvature of their upper surface will vary to suit the varying arc 25 required by the round of the back to be produced.

The arms 39 carrying the back-forming roller 37 are operated to move in an arc of a circle of a radius corresponding to that 30 of the curve to be imparted to the back of the book against which said roller is caused to bear with the required pressure to complete the rounding of the back and by forcing the opposite edges over the clamped top 35 produce the required shoulder on each side.

The upper edges of the clamping plates 31 x are curved or beveled downward and the jaws 31 are cut away on the curvature corresponding to the arc described by the back-forming roller 37 to afford the necessary play to the latter to allow it to pass over on each side to the extent required to act upon the full surface of the back of the book.

The bearings 38 of the backing roller 37 45 are adjustable in the arms 39 to enable the arc through which the roller travels to be varied to suit the curvature of the back of the book being operated upon.

For the purpose of operating the arms 39 50 their outer extremities are by links 51 connected to one arm of bell crank levers 52 pivoted to the bar 33 fixed to the side frames 2, the other arm of said bell crank levers being connected by link 53 to lever 54 pivoted 55 to countershaft 15 and fitted with a roller 55 engaging a cam groove in the cam 56 mounted on cam shaft 18.

After the back forming operation has been completed by the action of the roller 37 the 60 latter is by the drawing back of the bracket or block 40, under the action of the toggle arms 41, withdrawn from over the book, which is thus left free for removal from the machine, after the clamping jaws 31 which 65 have held and maintained the book during

such backing have been first released under the action of their toggle arms 32.

This removal or delivery of the "rounded" and "backed" book from the machine is automatically effected by a second carrier 70 400 arranged to reciprocate longitudinally to bring same under the book a^x held by the clamping jaws 31 before said book has been released therefrom, said second carrier preferably as shown forming an extension of the 75 first carrier bar or frame 4 (but on a higher level) and sliding in grooves in the outer bar 300, and the two move synchronously. The rear of the upper carrier 400 also carries a hinged part or trigger plate 500 similar to 80 that carried by carrier 4 and which by similar means is on the rearward movement tripped so as to pass book a^x and then turned so as to engage the rear thereof and on the forward movement carry it along a supporting bar 300 and between longitudinal guide cheeks 100 to the position a^{xx} outside the machine, whence it can be removed either by hand or by a conveyer of any suitable construction. The hinged trip 700 attached to 90 one of the guide cheeks 100 effects the turning of trigger plate 500 on the backward travel of carrier 400, and the abutment 401 returns said plate to position behind the book to be removed before the carrier begins its next forward movement. The abutment 401 is secured in side frame 2 and is adjustable thereon to correspond with the 95 length of book being operated upon.

The book carrier, comprising the frame 4 100 and its extension 400, is operated by any suitable means. For effecting the feed stroke a flexible band 57, running over a pulley 59, has one end connected to the frame 4 at a convenient point as 58 and its other end connected to an outwardly swinging actuating lever 60 pivoted to one of the side frames 2. A link 61 pivoted to lever 60 by a universal joint connects said lever also by a universal joint to a lever 62 pivoted on a countershaft 105 15 and carrying a roller 63 engaging a cam groove in a cam 64 mounted on cam shaft 18. The return stroke is effected by a cord 61' running over a pulley 62' connected at its upper end to the frame 4 and carrying a 110 counterweight 65.

The whole of the movements of the different parts of the machine are so synchronized that the feed of the books to the machine, the passage of same therethrough and the delivery therefrom are all effected automatically and continuously without necessitating any hand labor from the point a where the books are received to the point a^{xx} at which they leave. As the lower or feed carrier 115 moves to engage a fresh book which has been deposited upon the supporting bar 3 the upper or delivery carrier 400 passes to the rear of the backed book a^x supported in the clamping jaws 31, leaving the one pre- 130

viously received from such jaws behind it at the point of delivery $\alpha^{\prime\prime}$. Between the forward and backward movements of the carriers 4, 400, the book resting on the movable section 3 $\times$ of the supporting bar 3 is raised between the rounding rollers 12 which convey it to position between the clamping jaws 31, such movable section returning to its lower position in time to receive the next book from the feed or lower carrier 4 on its next forward movement.

The carriers 4, 400, may be each of a length to receive two or more books end to end and to convey them to position beneath the rounding rollers 12 to which they will be raised so as to pass together and be acted upon simultaneously by the rounding and backing roller 37, and subsequently together conveyed by the upper carrier 400 to the point of delivery $\alpha^{\prime\prime}$.

As hereinbefore stated the distance between the guide cheeks 1 between which the feed of the books to the machine is effected, may if desired be adjustable to enable the machine to be used for rounding and backing books of varying thickness, and similarly the travel of the feed and supply carriers 4, 400, the lift of the movable section 3 $\times$ of the supporter bar 3, the distance between the rounding rollers 12 and the movable section 3 $\times$ of said supporter bar on which the books rest in succession, as also the length of such lift, the distance between the rounding rollers 12 themselves, the distance of said rollers from the gripping jaws 31, as also the distance of the latter apart, and finally the arc through which the rounding and backing roller 37 moves, and the extent of the transverse displacement of such roller, and all of which will be regulated to suit the particular size and thickness of book to be operated upon, may if necessary or desirable all be capable of adjustment within certain limits to enable the machine to be employed for effecting the backing and rounding of the backs of books of different sizes and thicknesses.

What I claim as my invention, and desire to secure by Letters Patent, is—

1. In a rounding and back forming machine for book binding the combination of elongated stationary guides adapted to hold the book sheets passed between them, a supporting bar disposed below said guides and provided with a convex upper surface adapted to contact with the front edges of said sheets, one section of said supporting bar being vertically movable, a pair of rounding rollers disposed above said guides, a pair of clamping jaws disposed above said rounding rollers, a reciprocating carrier adapted to engage said book sheets and slide them along said supporting bar between said guides, a back forming roller adapted to reciprocate in an arc corresponding to the

curve to be imparted to the back of the book, co-operative mechanism for actuating said bar section, rounding rollers, jaws and backing roller, and means for delivering said backed sheets.

2. A machine of the character described comprising elongated stationary guides adapted to hold the book sheets passed between them, a supporting bar disposed below said guides and provided with a convex upper surface adapted to contact with and shape the front edges of said sheets, said supporting bar being composed of sections, one of which is movable vertically, a supplementary bar also composed of sections, one of which is vertically movable, adjustable connecting means between said bars, and means for coupling and uncoupling the movable sections.

3. A machine of the character set forth comprising rounding rollers disposed side by side apart from each other, means for moving one of said rollers alternately toward and away from the other, means for entering book sheets between said rollers, clamping jaws disposed adjacent to said rollers, and means for rotating said rollers to enter the book sheets between said clamping jaws.

4. A machine of the character set forth comprising rounding rollers disposed side by side apart from each other, means for moving one of said rollers alternately toward and away from the other, means for entering book sheets between said rollers, clamping jaws disposed adjacent to said rollers, means for rotating said rollers to enter the book sheets between said clamping jaws, and means for adjusting the relative movement of said movable roller to suit books of different thicknesses.

5. A machine of the character set forth comprising rounding rollers disposed side by side apart from each other, means for moving one of said rollers alternately toward and away from the other, means for entering book sheets between said rollers, clamping jaws disposed adjacent to said rollers, means for rotating said rollers to enter the book sheets between said clamping jaws, a backing roller, and means for oscillating said backing roller in contact with the projecting edges of said sheets while they are held between said jaws.

6. A machine of the character set forth comprising rounding rollers disposed side by side apart from each other, means for moving one of said rollers alternately toward and away from the other, means for entering book sheets between said rollers, clamping jaws disposed adjacent to said rollers, means for rotating said rollers to enter the book sheets between said clamping jaws, means for oscillating said backing roller in contact with the projecting edges

of said sheets while they are held between said jaws, said clamping jaws having interchangeable gripping checks of varying height and thickness and of different curvature at their tops to suit different sizes of books.

7. A machine of the character set forth comprising jaws for holding the sheets to be backed, a sliding block, arms pivoted to said sliding block adjacent to opposite ends of said jaws and provided with vertical guideways, bearings adjustable in said

guideways, a lever, links connecting said lever with the upper ends of said arms, a backing roller supported in said bearings, and 15 means for actuating said sliding block and lever.

In testimony whereof I have signed my name to this specification in the presence of two subscribing witnesses.

JOHN L. MERCER.
